NAIL CLEANING ATTACHMENT FOR NAIL FILES

Richard C. McRoberts, Tama, Iowa

Application February 17, 1944, Serial No. 522,775

5 Claims. (Cl. 132—73)

This invention relates to improvements in finger nail files, wherein means associated with the file are provided for dislodging accumulations from under the finger nails, the said accumulations ordinarily being referred to as "dirt."

In the employment of ordinary means for removing accumulations from under the finger nails, the dirt is forced into a mass under the nails and its removal becomes more troublesome than is the case if the dirt is cut away or removed piece-meal and before it can be compressed ahead of the instrument used when cleaning the nails. Hence, it is an object of the invention to provide an attachment for finger nail files which will accomplish the removal of the dirt without compressing it.

It is a further object of the invention to provide the said means for accomplishing the foregoing results at the point of such files, and the same has proven simple in character, efficient and satisfactory in use, and comparatively inexpensive.

With the foregoing and other objects in view, the invention consists in the details of construction, and in the arrangement and combination of parts to be hereinafter more fully set forth and claimed.

In describing the invention in detail, reference will be had to the accompanying drawing forming part of this application, wherein like characters denote corresponding parts in the several views, and in which:

Figure 1 illustrates a view in perspective of a fragment of a file showing a cleaning instrumentality embodying the invention applied thereto;

Figure 2 illustrates a perspective view showing fragments of the installation detached;

Figure 3 illustrates the utility of the invention in removing dirt;

Figure 4 illustrates the manner in which the dirt is piled or compressed under the finger nail in an attempt to remove it by the use of an ordinary nail file; and

Figure 5 illustrates a plan view of a file with modified cleaning means formed as a part of files now in common use.

In the present embodiment of the invention a nail file 1 is shown as having a dirt removing means at its end which comprises a length of wire doubled on itself to form a loop 2 the ends 9 of which wire embrace the edges of the file at its outer end, and preferably the end of the file is reduced to form shoulders 10, against which the ends 9 of the wire abut; it being shown

that the end of the file is reduced in width so that the wire embracing the said end may be secured in position by a clamp or clip 11 surrounding the assembled parts, and the clamp 5 may be pressed into place or secured in any suitable manner, as by spot welding or the like. The wire is preferably of steel, such as piano wire, or the like, and it has one surface ground so that it is approximately semi-circular in cross section and has cutting edges 12 and 13. The foregoing parts, it will be observed are substituted for the nail cleaning end of the ordinary nail file. It is shown that the length of metal or wire has the outline of an acute angle and is semi-circular in cross section throughout its length. The curved surfaces of what may be termed the arms which extend from the loop oppose each other, whereas the flat surface of the fabricated member is on the outer surface of the said arms, and are perpendicular to a plane containing both arms of said angle. It is seen from an inspection of Fig. 3 that the edge of the scraper operates to dislodge deposits from the finger nail and that the scrapings or deposits when dislodged escape through the space inside of the angularly disposed portions of the scraper.

As a modification of the dirt cleaning device described, the end 14 of an ordinary finger nail file may be stamped or cut away to form an opening therein through which dirt dislodged from the finger nail escapes, and the edges 15 and 16 of the end may be sharpened to form cutting edges which will serve to dislodge dirt in much the same manner as that resulting from the use of the first mentioned embodiment, and either form of this invention may be produced without materially adding to the expense of finger nail files now ordinarily employed.

Figure 3 illustrates the action of the finger nail cleaner of the invention when operating underneath and relative to the finger nail 17 which is shown in cross section, whereas Figure 4 illustrates the action of an ordinary nail file when acting on dirt as it is being removed from such a finger nail 17.

I claim:

1. A nail cleaning instrumentality comprising a length of metal doubled on itself to form an approximately V-shaped loop, said metal being approximately semi-circular in cross section with a convex inner surface and a straight outer surface having scraping edges at the junction of the convex and straight surfaces, and a member carrying the said instrumentality.
2. A nail cleaning device for dislodging scrap-

ings from finger nails comprising a length of metal fabricated to an acute angle, the material being semi-circular in cross section throughout its length, the curved surfaces of the angularly disposed portions of the metal being adjacent to one another and the flat surface of each portion being the outer surface of said angle, which surfaces are perpendicular to a plane containing both portions of said angle.

3. A nail cleaning device made of suitable material having a formed apertured point, the material at the edge of the aperture being convex and the outer edge of the material at the point being straight, whereby scraping edges are formed at the junction of the said convex inner surface and the straight outer surface, as and for the purpose described.

4. A nail cleaning device formed of a loop of relatively fine wire material, one surface of said material being convex and the opposed surface being straight, with scraping edges formed at the merger of the convex and straight surfaces.

5. A nail cleaning device comprising a length of relatively fine wire material doubled on itself to form an approximately V-shaped loop, the material of the loop being angular in cross section, the apices of which angles form scraping edges and the sides of the material forming the angles impinging and moving deposits from the finger nails as the cleaning device is manipulated.

RICHARD C. McROBERTS.
